[57] CLAIM

The ornamental design for a bench, as shown and described.

DESCRIPTION

FIG. 1 is a front perspective view of a bench showing my new design;

FIG. 2 is a rear perspective view of the bench of FIG. 1;

FIG. 3 is a front elevational view of the bench of FIG. 1;

FIG. 4 is a front perspective view of a second embodiment of the bench of FIG. 1;

FIG. 5 is a front perspective view of a third embodiment of the bench of FIG. 1;

FIG. 6 is a side elevational view of the bench of FIG. 5 on an enlarged scale, the opposite side being a mirror image thereof; and

FIG. 7 is a rear elevational view of the bench of FIG. 5.
